UNITED STATES PATENT OFFICE.

TORBJÖRN LINGA, OF THOR, IOWA, ASSIGNOR TO AMERICAN DITCHING MACHINE COMPANY, OF WEST MINNEAPOLIS, MINNESOTA, A CORPORATION OF MINNESOTA.

DITCHING-MACHINE APPARATUS.

1,152,524.

Specification of Letters Patent. Patented Sept. 7, 1915.

Application filed September 30, 1910. Serial No. 584,693.

To all whom it may concern:

Be it known that I, TORBJÖRN LINGA, a subject of the King of Norway, residing at Thor, in the county of Humboldt and State 5 of Iowa, have invented certain new and useful Improvements in Ditching-Machine Apparatus, of which the following is a full, true, clear, and exact description.

My invention pertains to ditching machines and particularly to ditching machines 10 of the type employed in digging ditches or trenches for drainage or sewerage purposes.

The object of my invention is to provide a ditching machine with means coöperative 15 with the digging element which will enable the ditching machine to dig a ditch or trench through soft or sandy or yielding soil, and at the same time sustain or support the sides of the ditch behind the machine against caving in or collapsing as the digging operation 20 goes on and which will be constructed and arranged in such a manner that it will leave a clear, open space immediately in the rear of the digging element to enable a workman 25 to safely, conveniently and efficiently lay tiling or piping in the bottom of the ditch.

Another object of my invention is to provide a ditching machine with means which 30 will prevent any of the dirt dug by the digging device from falling or sifting back into the ditch upon the workman who is laying tiling or piping therein and which will co-operate in producing at the rear of the digging device a clear, open space in which the 35 workman may work.

Still another object of my invention contemplates the provision of a ditching machine having means associated with the digging element thereof for shaping or sloping 40 the sides of the ditch when the ditch is dug through sandy or loose ground which is inclined to cave in, so that the sides of the ditch will be self-sustaining and the ditch or trench may be left open.

Another object of my invention is to so 45 arrange these various parts that they may be quickly and easily placed in their operative positions or removed therefrom, and further that they may be comparatively inexpensive to manufacture and replace in case they become damaged.

My invention contemplates a ditching machine comprising a movable truck and a digging element carried thereby and bodily 50 movable relatively thereto, in combination

with a guard or crummer mounted adjacent to said digging element to prevent any dirt from sifting or falling back into the ditch, and a protector shield supported in position adjacent the sides of the ditch and supporting or maintaining the sides of the ditch against collapsing or caving in, the guard and protector shield being so constructed and related that they provide immediately behind the digging element a 60 clear, open space as the digging operation proceeds in which space a workman may follow the machine and lay drainage piping or tiling.

My invention further comprises a ditching machine having a guard and protector shield, as above mentioned, in combination with plates positioned within the digging element at the sides thereof and arranged to sustain the sides of the ditch from caving in 70 and interfering with the operation of the digging element; and further my invention comprises cutting or trimming devices positioned at the sides of the digging element and so arranged that as the digging element is digging a ditch or trench the cutting devices cut away or slope upwardly the sides of the ditch thereby making a ditch which is wider at the top than at the bottom and rendering the sides of the 80 ditch self-sustaining.

My invention further consists in a ditching machine having the above described structures so arranged and related to each other and to the machine and so constructed 90 and arranged that they are readily removable for repair and as readily replaced in position.

One embodiment of my invention is shown 95 in the accompanying drawings in which:

Figure 1 is a side elevation of the rear portion of a ditching machine truck and the digging wheel carried thereby, the guard, the protector shield, the plates and knives being shown in their relative working positions; Fig. 2 is a sectional view on line 2—2 of Fig. 4; Fig. 3 is a top plan view of the rear portion of the truck and digging wheel showing the protector shield; Fig. 4 is a view on line 4—4 of Fig. 1 showing the digging wheel in section and the cutting knives and a portion of the guard in their relative positions; Fig. 5 is a vertical sectional view on line 5—5 of Fig. 6 showing the protector shield and a portion of the crummer or 100 105 110

guard; Fig. 6 is a sectional view on the line 6—6 of Fig. 1.

Like parts will be characterized by similar reference numerals throughout the several views.

The ditching machine which I have shown in the drawings forms the basis of the subject matter of Patent No. 910,552 issued to me January 26, 1909; it comprises a truck represented generally as 1 and a digging member or wheel 2. The truck 1 is provided with a rear axle 4 upon which the rear traction wheels of the truck are mounted, and about which, as a center, the digging wheel 15 2 is bodily raised or lowered in a vertical plane. Upon this axle is pivoted the clevis yoke 3 to the inner end of which, adjacent its pivot, is secured, at substantially right angles thereto, an upwardly curved framework 5. The clevis yoke 3 and framework 5 are rigidly connected together by the brace rods 6, and together they constitute a bell crank lever mounted to swing or revolve vertically about the axle 4 as a pivotal center.

Between the outer ends 9 of the clevis is rotatably mounted the digging wheel or member 2, this wheel being rotated, by suitable gear mechanism and a source of power (not shown) to perform its digging operation. The digging member 2 comprises a spoked wheel having outer and inner rims 2^a and 2^b, respectively, concentrically disposed one within the other and spaced apart by the central rib or web 2^c and forming between them a continuous groove or channel on each side of the rib 2^c. The outer rim 2^a is provided with a series of transverse slots 10^a adjacent the edges of which and projecting angularly therefrom are the cutting blades 10, these blades 10 being adapted to shave or slice the dirt and direct it into the grooves or channels between the rims where it is retained and carried to the top of the wheel 45 and there removed by plows 11 which deflect the dirt on to the conveyer mechanism 12 by which it is finally discharged and distributed along the sides of the ditch. The conveyer mechanism is supported upon the uprights 12', the lower ends of which are pivoted on the short shaft 9' extending between the outer ends 9 of the clevis yoke 3. The bell crank lever, which carries the digging wheel 2, is swung about its pivotal axis 50 4 by means of the hoisting mechanism 8 carried in the roof of the truck and operated through the medium of the chain 7 connected to the outer end of the framework 5. By this arrangement the digging wheel is lowered into the ground to any depth to which it is desired to dig a ditch or it is raised up clear of the ground when the machine is traveling from place to place. The conveyer mechanism 12 is maintained in its relative position to the top of the digging

wheel 2, that is, it is maintained in a substantially vertical position at all positions of the digging wheel 2 by the link rods 12^a extending between and pivotally connected to the rear uprights or roof supports on the truck and the bridge beam of the conveyer mechanism.

Secured at its upper end 15^a to the conveyer mechanism 12, and extending downwardly adjacent the rear side of the digging wheel 2, is a guard or crummer 15. This guard or crummer is preferably built up of a number of plates curved longitudinally and transversely and joined end to end to form a rigid continuous structure which conforms to the contour of the periphery of the digging wheel. The guard is provided with a central longitudinal ridge or rib 15' throughout its entire length which forms an internal groove or channel for the gear teeth 80 on the periphery of the digging wheel and which in addition serves as a strengthening rib for the guard. The guard extends from the conveyer mechanism 12 downwardly adjacent the rear of the wheel through substantially 180 degrees to a point very close to the bottom of the ditch where the cutting blades 10 on the digging wheel are cutting the dirt. Between the lower end and the middle portion of the crummer, on each side 95 thereof, the braces 13 and 14 extend forwardly therefrom, these braces lying principally within the side planes of the wheel and extending to the outer ends of the clevis yoke where they are pivotally mounted upon the shaft 9'

As before stated, the blades on the periphery of the digging wheel 2 shave or slice the dirt and direct it between the outer and inner rims 2^a and 2^b where it is retained and carried to the top of the wheel. The plows 11 on the conveyer mechanism project into the spaces between the rims and deflect the dirt laterally on to the conveyer mechanism. Should any of the dirt pass the plows it will fall against the inner surface of the guard 15 and will be directed by the crummer downwardly to the bottom of the ditch where it is again picked up by the blades on the digging wheel.

Ditching machines of this class used for drainage work are often required to dig a ditch or trench in ground of such character that the walls of the ditch are liable to cave in immediately behind the machine and, since a workman usually follows very close in the rear of the digging wheel, he is prevented from properly performing his work of laying tiling or piping by the caving in of the walls of the ditch. I have provided a 120 hollow box-like structure or protector shield 20, removably secured to the guard 15. This structure trails along back of the digging wheel in a position substantially or wholly within the ditch, the side plates 22 of this 125 130

shield being very close to or in contact with the walls of the ditch and overcoming any tendency of the walls of the ditch to cave in or to collapse; in fact serving as a temporary curbing for the walls of the ditch. The edges 21 of the side plates are curved to conform to the curvature of the crummer and are removably secured adjacent the side edges thereof. The opposite or rear edges 10 of said plates are spaced apart by means of a transverse plate 24 fastened in place by bolts or otherwise. Secured to the lower edges of the plates and projecting inwardly, at right angles thereto, are the flanges 25 15 upon which a suitable seat may be placed for the workman or a suitable tray for his material. The shield 20 is secured to the crummer in any suitable manner. In the drawings I have shown the said plates there- 20 of provided with lugs 26 bolted thereto on the inner faces and carrying downwardly extending pins 27 adapted to register with and to be inserted into pin holes provided in the lugs 28 bolted to the guard 15 adjacent 25 the side edges thereof. It will thus be seen that this shield effectively overcomes any inclination of the sides of the ditch to cave in, at the same time it provides between the side plates thereof a clear, open space in 30 which the workman may safely and conveniently perform his work. In addition to the shield 20 I have provided a set of plates 34 disposed within the circumference of the digging member. The plates are 35 removably secured, as by bolts, to the braces 13 and 14; a plate being provided on each side of the digging member 2 and lying substantially in the side planes of said member. These plates effectively sustain the walls of 40 the ditch adjacent the sides of the wheel from caving in and interfering with the operation of the wheel.

A part of my invention comprises the cutting knives or blades 30 and 18 mounted on each side of the digging wheel. The cutting knives 30 are disposed diagonally and are bolted or otherwise removably secured at their lower ends to the braces 14. These 45 blades or knives are so constructed that they 50 diverge upwardly and outwardly until their upper ends reach a point substantially coincident with the outer ends 9 of the clevis yoke, these ends 32 being then turned inwardly and removably pivoted on the shaft 55 9'. The cutting blades or knives 18 are secured at their upper ends directly to the clevis yoke 3 and at their lower ends to the brace bars 19 which are secured to the clevis 3. These knives 18 depend diagonally 60 to a point below the hub of the digging wheel. They are disposed to lie along the same lines of convergence as the cutting blades. Both sets of knives 30 and 18 are 65 preferably secured in position in any suitable manner so that they may be conven-

iently removed in case it is not desired to use them. The function of these cutting blades 30 and 18 is readily apparent. They slice or shave off the walls of the ditch in such a manner that the walls of the ditch 70 diverge upwardly and outwardly. Thus they coöperate with the digging member to dig a ditch which at its bottom is substantially the width of the digging member and at its top is wider than the width of the 75 digging member; a ditch of this character being particularly desirable where it is intended that the ditch shall be left open. The guard 15, the protector shield 20 and braces 13 and 14 and the cutting knives 30 30 are all related to each other and to the digging member and secured together in such a manner that in a sense they constitute a rigid framework, which framework is pivotally supported at one point by the outer 85 ends 9 of the clevis yoke and at another point by the conveyer mechanism 12. The various devices or constituent parts which make up this framework are maintained in their proper relation to the digging member 90 and to the ditch at all times during the operation and position of the digging element by the parallel link rods 12a. Furthermore, these parts are all constructed and arranged so that they are readily removable either for 95 repair or when it is desired to operate the ditching machine without them.

I claim:

1. In a ditching machine the combination with a movable truck, of a digging wheel, an arm pivotally mounted at one end upon the truck and carrying the wheel rotatably mounted at its free end, means for moving the arm on its pivot to position the wheel vertically for digging ditches of different 105 depths and for raising the wheel clear of the ground, a dirt guard extending from the top to the bottom of the wheel surrounding the rear periphery thereof and adapted to direct dirt from the top of the digging wheel 110 to the bottom of the ditch, and means for automatically maintaining the guard in position with its upper end at substantially the topmost point of the wheel regardless of the depth of ditch being dug. 115

2. In a ditch digging machine the combination with a movable truck, of a digging wheel, an arm pivotally mounted at one end upon said truck and carrying said wheel rotatably mounted at its free end, means for raising and lowering the arm to position the wheel vertically for digging ditches of different depths and for raising the wheel clear of the ground, a standard pivotally connected with the free end of said arm 120 rising therefrom and spanning the wheel, means for maintaining said standard in vertical position regardless of the relative height of the wheel, a wheel guard extending over the rear portion of the wheel and 125 130

- having its upper end connected with said standard, whereby the upper end of said standard is maintained at all times at the topmost point of the wheel, and guard supports pivotally connected at the center of the wheel and extending rearwardly to said guard to maintain the lower end thereof properly spaced from the periphery of the wheel.
10. 3. In a ditching machine, a truck and a digging wheel carried thereby and movable therewith, a lever pivotally mounted at one end to the rear end of the truck and carrying the wheel rotatably mounted on its free end, in combination with a dirt guard and protector shield associated with said digging wheel, said guard directing dirt from the top of the wheel to the bottom of the ditch and said protector shield maintaining the sides of the ditch against collapse and means connecting the guard and shield to said pivoted arm and to the truck for automatically maintaining said devices in a fixed relation to the vertical diameter of the wheel and the bottom of the ditch.
15. 4. In a ditching machine, a truck, an arm arranged to move vertically and pivoted at its forward end to the rear end of the truck, a digging wheel rotatably mounted on the rear end of the arm, a dirt guard arranged adjacent to the rear side of the wheel and adapted to direct dirt from the top of the wheel to the bottom of the ditch, a protector shield carried by the guard and adapted to prevent the collapse of the sides of the ditch and means connecting said guard and shield with the free end of said arm and with the truck and adapted to hold the guard and shield in fixed positions relatively to the bottom of the ditch and to the vertical diameter of the wheel regardless of the position of the movable arm.
20. 5. In a ditching machine, the combination with a digging wheel vertically adjustable in circular arc, of a peripheral guard adjacent said wheel concentrically mounted with respect to the axis thereof and extending from the top of said wheel to substantially the bottom of the ditch dug by said wheel, a protector shield fitted to and carried by the guard and supporting the sides of the ditch and means for supporting said guard and shield in a fixed relation to the horizontal diameter of the wheel regardless of the height of the wheel.
25. 6. In a ditching machine the combination with a digging wheel, vertically adjustable in a circular arc, of a protector shield supporting the sides of the ditch dug by said wheel, said shield being mounted adjacent the rear portion of said wheel and trailing along immediately behind said wheel, dirt supporting plates mounted within the digging wheel and maintaining the sides of the ditch adjacent said plates against collapse and mechanism connecting said shield, plates and wheel and maintaining said shield and plates in fixed positions relatively to each other and to the horizontal axis of said wheel.
7. In a ditching machine, the combination with a propellable truck of a digging wheel carried thereby, a vertically swinging arm pivotally mounted at its forward end upon the truck and carrying the wheel rotatably mounted upon its free end, means for raising and lowering the arm to position the wheel vertically relatively to the truck, a box like structure positioned at the rear of the wheel and adapted to follow the wheel through the ditch being dug, the sides of the box-like structure supporting the sides of the ditch against collapse and mechanism connecting the box-like structure to said arm and to the truck and maintaining it in a definite fixed relation to the bottom of the wheel and to the bottom of the ditch.
8. In a ditching machine, a movable truck, an arm pivoted on the rear end thereof and arranged for vertical movement, a digging wheel rotatably mounted on the free end of said arm, a crummer concentrically mounted with respect to the rear portion of said wheel and extending through an arc of substantially 180 degrees, the crummer being pivotally supported on said arm at the axis of rotation of the digging wheel and means connecting the upper end of said crummer with the truck and with said arm and adapted to hold the lower end of the crummer in a definite relation to the bottom of the ditch.
9. In a ditching machine, a digging wheel carried at the rear end thereof and movable vertically to dig ditches of different depths, a lever pivoted at its forward end to the rear end of the truck and carrying said wheel rotatably mounted at its rear end, means for raising and lowering said lever, a crummer supported adjacent to the rear portion of said wheel and conformed to the curvature thereof, a box-like structure carried by said crummer and adapted to pass through the ditch dug by the wheel, the side faces of said structure extending rearwardly from said crummer and substantially parallel to and supporting the sides of the ditch dug by the wheel and means connecting said crummer and structure to the free end of said arm and to the truck and adapted to maintain them in a definite relation to the horizontal diameter of the wheel and to the bottom of the ditch.
10. In a ditching machine, a movable truck, a digging wheel carrying arm pivotally mounted at the rear end of the truck and movable vertically, a digging wheel rotatably mounted on the free end of the arm, a guard mounted in close proximity to the rear portion of said wheel and a protector shield preventing the sides of the ditch from

caving in, said shield being positioned substantially below the surface of the ground when the wheel is in digging position, supporting plates positioned within the circumference of the wheel for supporting the sides of the ditch adjacent thereto, brace bars pivotally connected at their forward ends to the rear end of said arm and adapted to maintain said guard, protector shield and plates in definite relative positions, means connecting the upper end of said guard with the truck adapted to maintain the guard, the shield and the plates in a definite position relative to the horizontal diameter of the wheel regardless of the relative position of said arm.

11. In a ditching machine the combination with a wheeled support, of a digging wheel, an arm pivotally mounted at one end upon said support and carrying said wheel rotatably mounted at its free end, means for rotating said arm on its pivot to position the wheel vertically for digging ditches of different depths and for raising the wheel clear of the ground, a standard pivotally connected with the free end of said arm, uprising therefrom and spanning the wheel, means for maintaining said standard in vertical position regardless of the height of the wheel, a wheel guard extending over the rear portion of the wheel and having its upper end connected with said standard, guard supports pivotally connected at the center of the wheel and extending rearwardly to said guard, and a box-like structure extending rearwardly from said wheel supported by said guard and adapted thereby to be held in a definite relation to the

bottom of the ditch regardless of the depth thereof, the side walls of said box supporting the sides of the ditch.

12. In a ditching machine the combination with a wheeled support, of a digging wheel rotatably mounted upon a horizontal axis and vertically adjustable in a circular arc and means connecting the wheel with the wheeled support adapting it for said adjustment, a circular guard covering the rear portion of the periphery of the wheel, and means for maintaining said guard in definite relation to the bottom and top of the wheel regardless of the position of the wheel, guard supports extending horizontally from the center of the wheel rearwardly to the guard, and sloping knives carried by said guard supports and held thereby in definite relation to the bottom of the wheel and to the sides of the ditch dug by the wheel.

13. In a ditch digging machine a truck and a digging wheel carried thereby and movable therewith, a vertically swinging arm upon which the wheel is rotatably mounted, a crummer at the rear side of the wheel to direct dirt from the top to the bottom of the wheel, and a box-like structure detachably mounted upon the lower part of the crummer adapted to support the sides of the ditch being dug.

In testimony whereof, I have hereunto set my hand this 9th day of September, 1910, in the presence of two subscribing witnesses.

TORBJÖRN LINGA.
